UNITED STATES PATENT OFFICE.

RUDOLF ROSNER, OF CHICAGO, ILLINOIS.

BLOWER.

1,346,796.

Specification of Letters Patent. Patented July 13, 1920.

Application filed January 23, 1920. Serial No. 353,467.

To all whom it may concern:

Be it known that I, RUDOLF ROSNER, a citizen of the United States, residing at Chicago, in the county of Cook and State of Illinois, have invented certain new and useful Improvements in Blowers, of which the following is a specification, reference being had to the accompanying drawings, forming a part thereof.

10 The purpose of this invention is to provide an improved construction of an air blower, particularly designed for insuring a steady and unvarying velocity of air discharge for a given speed of rotation, and 15 thereby especially adapted for certain therapeutic uses. It consists in the elements and features of construction shown and described as indicated in the claims.

In the drawings:—

20 Figure 1 is a vertical axial section of a blower embodying this invention.

Fig. 2 is a side elevation of the same with one of the case members removed showing the rotor in side view.

25 Fig. 3 is a detail section at the line, 3—3, on Fig. 2.

The blower shown in the drawings comprises two fixed standards, 1 and 2, upon and between which there is mounted the 30 blower casing, comprising two similar members, 3, 3, facing each other and making air-tight junction at their periphery for inclosing the rotor, 4. The case members have each a central aperture, 3^a, and they are 35 mounted upon the standards by means of annular fillet-and-groove features seen at 1^b, 3^b, the fillets being formed on the outer faces of the case members respectively, and the grooves upon the inner faces of the standards 40 respectively, so that the case when mounted upon and between the standards is rotatable with respect to the standards about the axis of the rotor. The rotor is journaled in the standards, or one of them, 45 having its axle or shaft upon which it is fixed, 5, extending through the central aperture of the case member for obtaining its journal bearing in the extended journal, 1^c, of the standard. As illustrated in the drawings, only one of the standards is provided 50 with a journal for the rotor. The other standard is provided with an air inlet connection, 1^d, co-axial with the rotor and with the central apertures of the casing. This 55 specific construction,—with one air inlet and one bearing for the rotor,—is convenient for

certain uses for which the blower shown is designed, but is not a characteristic of the invention herein claimed.

The detail form of the rotor is designed 60 to overcome or avoid a defect generally discovered in blowers of this general type when they are applied to uses requiring uniform velocity of the air current delivered, as in certain therapeutic devices and apparatus. 65 It is known that in blowers of common construction, there result eddies and vortices in the air movement which at some particular speed of the rotor, tend to cause accumulating back pressure which is relieved by 70 spasms or instants of sudden dropping of speed, accompanied by more or less violent vibration of the blower. These vortices and eddies I have ascertained, result from the conflict of the normal centrifugal flow of air 75 outward along the fan blades with what may be termed "knife blade" blasts of air passing laterally by the fan blades or air-driving arms, which are necessarily not fitted air-tight in the casing, but run clear 80 of the inner surfaces of the casing by a distance sufficient to insure avoidance of actual contact and the friction which would result from such contact. The structure of the rotor herein shown in respect to the fan blades 85 or air driving arms overcomes this trouble, by producing an air packing between the casing and the air driving arms or blades. This is done by forming these arms, 4^b, with air pockets, 4^c, at their opposite sides open 90 toward the casing walls respectively, said pockets being also open at their inner ends, at 4^d, and closed at their outer ends, so that the centrifugal action causes the air to be packed or compressed in these pockets, and 95 also so that the air compressed in advance of the air-driving arm, and driving or tending to drive between said arms and the walls of the casing, and tending to expand into the pockets as it passes them, is thereby 100 obstructed and halted, and additionally opposed by the air compressed in the pocket by the centrifugal action mentioned; and thereby the "knife-blade" blasts mentioned are substantially prevented.

105 The pocket formation of the arms, 4^b, is produced by making them each comprise a web, 4^f, in the plane of rotation, and a transverse flange, 4^g, which constitutes the air-driving face, an end flange, 4^h, and a 110 second flange, 4ⁱ, parallel to 4^g, but extending only to the edge of the central air inlet

aperture of the casing. I have found that a second transverse flange at a distance back in the direction of rotation from the flanges, 4^g, and 4^h, operates to further obstruct the 5 knife blade air blast. This flange, 4^k, is extended from the end flange, 4^h, and deflected as seen at 4^m, for junction with the web, 4^f. This formation results in a through-and-through aperture, 4ⁿ, from side 10 to side of the arm, 4^b, which constitutes a communication between the two pockets, 4^e, at opposite sides of the arm. And this communication has an important function in equalizing the pressure in the two pockets. 15 That the pressure developed in the pockets, 4^e, is very considerable, is proven by the fact that when the pockets are present the casing is sensibly bulged when the blower is in operation at high speed, such bulging 20 being in excess of that which is observable when the rotor is without these pockets. I have found that uniformity of the air velocity is greatly assisted by making the periphery of the air relief passage around the ends 25 of the arms, 4^b, helical in form as shown, the shortest radius of the helix being slightly greater than that of the rotor, and said helical periphery extending substantially 360 degrees around the axis of the rotor, so that 30 the discharge connection occurs substantially opposite the shortest radius.

I claim:

1. In a centrifugal blower, in combination with a case having a central air inlet, 35 a rotor in the case comprising air driving arms whose width approximately spans the air cavity of the case, and which have on their opposite sides toward the opposing walls of the case air pockets open toward 40 said walls and closed at the outer ends of the arms and open at the inner ends thereof.
2. In the structure defined in claim 1 foregoing, the two pockets at opposite sides of each arm having limited air communication with each other within the area of the arm abutting on the case wall.
3. In the structure defined in claim 1 foregoing, each arm having the air pockets occupying a limited portion of the area of the

arm abutting the case wall, said arms being 50 apertured through their entire width from case wall to case wall over an area extending alongside that occupied by the pocket; the partition between said pocket and said through-and-through apertures being cut 55 away for a short distance along the inner end portion of the pocket for limited communication between the pockets at said two opposite sides.

4. In the structure defined in claim 1 60 foregoing, the air driving arms each comprising for forming the pockets mentioned a web, 4^f, having a flange, 4^g, transverse to the plane of the web, extending along the forward edge of said web, thence across the outer end of the web and thence back inwardly a certain distance along the course of the web, and spaced off therefrom approximately the width of the web, and then flexed to and projected partly across the web toward but not reaching the forward edge flange; and a second flange extending transversely to the plane of the web along the rear edge thereof from the outer end to within a short distance of the junction of 75 the flexed flange with the web; whereby there is formed in each arm two pockets upon opposite sides thereof, and a through-and-through passage alongside said pocket, at the inner end.

5. In a blower, in combination with two opposed standards, centrally apertured case walls carried by said standards respectively, and a rotor journaled in the standards, the case wall and standards having annular 85 fillet-and-groove engagement with each other co-axial with the rotor, and means for holding the standards together to embrace the case members between them; one of the standards having an air inlet conduit opposite the central aperture of the adjacent case member, and an air discharge conduit connected to the periphery of the case.

In testimony whereof, I have hereunto set my hand at Chicago, Illinois, this 21 95 day of January, 1920.

RUDOLF ROSNER.
